His Attorney.

UNITED STATES PATENT OFFICE.

FREDERICK P. FISCHER, OF CHICAGO, ILLINOIS.

SMOKE CONSUMER.

Application filed May 13, 1920. Serial No. 380,961.

To all whom it may concern:

Be it known that I, FREDERICK P. FISCHER, a citizen of the United States, and a resident of the city of Chicago, county of Cook, 5 and State of Illinois, have invented certain new and useful Improvements in Smoke Consumers, of which the following is a specification.

My invention relates to new and useful 10 improvements in smoke consumers, and has for its object the provision of a smoke consumer, which will be simple in structure, economic of manufacture and highly efficient in use. Another object is the provision 15 in a smoke consumer of means for delivering live steam and exhaust steam into the combustion chamber of a fire box. Another object is to provide a smoke consumer insertable in the combustion chamber of a 20 fire box which will be adapted to deliver air and steam over a large area of the combustion chamber.

Other objects will appear hereinafter.

The invention consists in the combinations 25 and arrangements of parts hereinafter described and claimed.

The invention will be best understood by reference to the accompanying drawings forming a part of this specification, and in 30 which,

Fig. 1, is a central, vertical, sectional view of the invention,

Fig. 2, a top plan view showing parts in section,

Fig. 3, is an end elevational view of the invention.

The preferred form of construction comprises a tubular member 6 which is flattened at one end 7, so as to present a narrow and broadened orifice. The tubular member 6 is adapted to be inserted through 40 the wall of the fire box so that the end 7 communicates with the interior of the combustion chamber. In mounting the member 6 in the fire box, the same is mounted in the most advantageous position so that air or steam driven through the end 7 will be delivered over the fire and deliver to the combustible matter contained in the fire box a

50 quantity of oxygen for assisting in the combustion. The opposite end of the member 6 is threaded into a reducer 8, the pipe 6 being threaded into the smaller end. The member 8 communicates with the exterior 55 of the fire box. Threaded into the opposite end of the tee is a nut 12 secured within

which is a pipe 13 which extends through the pipe 11 and beyond the inner or free end thereof. Secured to the outer end of the pipe 13 is a suitable elbow 14 connected 60 to a pipe 14' which is in communication with the steam exhaust of a boiler with which the device is used. The member 9 is in communication with the live steam, and at intervals when the device is in use, live 65 steam is turned on into the pipe 9. When the steam passes through the pipes 11 and 13, a suction is created which draws air inwardly through the open end of the member 8, and causes the same to discharge through 70 the end 7 of the pipe 6 into the combustion chamber.

As is readily understood by those skilled in the art, exhaust steam being nearer condensation than live steam, will when ejected 75 through the pipe 13 over the combustion chamber of a boiler, discharge a quantity of water vapor over the products of combustion in the chamber and thus manufacturing an artificial gas. The artificial gas thus 80 formed, commingling with atmospheric air, which is admitted through the pipes 6 and 8, causes the particles of combustion to be consumed, which would otherwise be discharged through the smoke stack of the 85 boiler. As herein mentioned, live steam is turned on into the pipe 9 at intervals and when desired, both exhaust and live steam can be used together as well as separately, the object being such that I find upon discharging the live steam separately or together with the exhaust steam, through the 90 orifice of the pipe 6, the suction of atmospheric air is greatly increased. This arrangement of the introduction of live steam 95 and exhaust steam into a combustion chamber of a boiler serves also as a fuel saver as well as a smoke consumer.

While I have illustrated and described the preferred form of construction for carrying my invention into effect, this is capable of variation and modification without departing from the spirit of the invention. I, therefore, do not wish to be limited to the precise details of construction set forth, but 100 desire to avail myself of such variations and modifications as come within the scope of the appended claim.

Having described my invention, what I 110 claim as new and desire to secure by Letters Patent is:—

A device of the class described including

- a tubular member having a flattened end portion and an orifice formed in said end portion, a reducer at the opposite end of said tubular member and open for the admission of atmospheric air, a steam pipe carried by said reducer and extending into the interior thereof and carrying a tee at the interior end, a pipe carried at one end of said tee and in communication with said steam pipe 5 and extending into the interior of said tubular member, a plug having a central opening formed therein at the opposite end of said tee, and a pipe passing through the opening

of said plug and said second named pipe and extending beyond the inner end of said pipe 15 for delivering water vapor to the interior of said tubular member to be ejected through said orifice by the steam from said second named pipe.

In testimony whereof I have signed my 20 name to this specification in the presence of two subscribing witnesses.

FREDERICK P. FISCHER.
